UNITED STATES PATENT OFFICE.

JOHN W. NOVAK, OF CLEVELAND, OHIO.

SLED ATTACHMENT.

Application filed January 10, 1923. Serial No. 611,806.

To all whom it may concern:

Be it known that I, JOHN W. NOVAK, a citizen of the United States, and a resident of Cleveland, in the county of Cuyahoga and

5 State of Ohio, have invented a new and Improved Sled Attachment, of which the following is a full, clear, and exact description.

This invention relates to improvements in sled attachments, and more particularly to improved means for controlling the movement of the sled either to steer the same, or to exert a braking action to stop the momentum or movement of the sled, an object of the invention being to provide an improved construction and arrangement of controlling means, which can be attached to any ordinary sled, which can be operated while lying flat upon the sled, or while in a sitting posture on the sled, and which will 15 function to permit a perfect control of the movement of the sled in accordance with the desire of the operator.

Children in coasting usually lie prone upon the sled and steer the sled by means of the toes bearing upon the ground. This results in wearing out the shoes, and is only partially effective, and it is the purpose of my invention to provide an attachment which will prevent this injurious wear of 25 the shoes and which at the same time will be entirely effective in operation, and by applying both prongs, cause the sled to stop, and prevent accidents.

With these and other objects in view, the 30 invention consists in certain novel features of construction and combinations, and arrangement of parts as will be more fully hereinafter described and pointed out in the claims.

40 In the accompanying drawings—

Figure 1 is a view in side elevation of a sled showing my improved attachment in operative position thereon.

Figure 2 is a view in longitudinal section 45 through the center of the sled, taken on the line 2—2, of Figure 3.

Figure 3 is a top plan view.

Figure 4 is a view in vertical transverse section on the line 4—4, of Figure 1.

50 Figure 5 is a fragmentary view in longitudinal section illustrating the supporting means for resisting the rearward movement of the prongs 9;

Figure 6 is a fragmentary view in section 55 on the line 6—6 of Figure 5.

A represents a sled which may be of any desired construction and which is provided with runners 1 secured to the body, or frame of the sled in any approved manner.

It is to be understood that my invention 60 is not limited to any particular construction of sled, but may be attached to any construction of sled and add but little additional cost to the same.

2, 2, represent a pair of levers which are fulcrumed between their ends on bolts or studs 3 supported in brackets 4 depending from the side rails of the sled, and fixed in any approved manner thereto.

Each lever 2 is preferably of angle iron 70 strengthened by a depending lug 5 with a truss rod or bar 6 projected across the same and fixed at its ends to the end portions of the lever.

75 Springs 7 are coiled about the studs or bolts 3, and at one end bear against the sled, and at their other ends are hooked over the forward portions of the levers 2 as shown at 8, to exert a downward pressure on the forward portions of the lever and elevate 80 the rear portions thereof which is their normal position.

At the rear ends of the levers 2, I provide downwardly projecting prongs 9 which are strengthened by guides 10 fixed to the 85 sled runners, and these guides are of such a shape as to receive the prongs and resist rearward bending action, yet allow free arcuate movement as may be desired.

90 It is of course to be understood that there is sufficient spaced relation between the prongs 9 and the guides 10 to allow the prongs to freely move with the levers moving on the fulcrums 3. Furthermore, this spaced relationship permits a certain 95 amount of flexing or resiliency to the prongs which is desirable but acts as a means for limiting rearward flexing movement when such movement might otherwise tend to break the prongs.

100 The prongs 9 are normally maintained with their lower ends in a plane above the lower surfaces of the runners 1 and are forced downwardly into engagement with the snow or ice by a fulcruming action of 105 the levers.

The forward ends of the levers 2 are located adjacent the forward ends of the runners 1, and are preferably made cylindrical and constitute handles 11 at their forward 110

ends so that the operator lying prone upon the sled can, with his hands, manipulate the levers as may be desired.

To permit the levers to be operated while the rider is in a sitting posture, I provide a pair of handles 12 pivotally connected to the sled, and having cams or turn buttons 13, at their inner ends engaging above the rear portion of the sled, so that by turning these handles 12 or exerting downward pressure thereon, the levers will be caused to fulcrum to project the prongs into the snow or ice.

In operation, while coasting, the rider causes the levers 4 to move independently or simultaneously either by a movement of the forward ends of the levers, or by the action of the handles 12, in accordance with his posture on the sled. If he desires to turn to the right, he causes the prong 9 at the right side of the sled to be projected downwardly, and if he desires to turn to the left, he causes the prong 9 at the left of the sled to be projected downwardly. If he desires to decrease the speed or to stop altogether, he causes both prongs to be projected simultaneously into the snow or ice.

By reason of an attachment of this character perfect steering control of the sled is had, and furthermore, a perfect braking action is had which not only results in a controlling of the action of the sled for the ease and comfort of the rider, but is in reality a safety device to prevent accidents and save life.

Various slight changes might be made in

the general form and arrangement of parts described without departing from my invention, and hence I do not limit myself to the precise details set forth, but consider myself at liberty to make such changes and alterations as fairly fall within the spirit and scope of the appended claims.

I claim:—

1. The combination with a sled, of a pair of levers fulcrumed between their ends and positioned longitudinally of the sled, prongs at the rear ends of the levers, springs normally holding the prongs in elevated position, the forward ends of the levers constituting handles, other handles pivotally connected to the sled at the rear of the lever fulcrums, and devices on the last-mentioned handles whereby when said handles are turned the prongs will be depressed.

2. An attachment for sleds, comprising a pair of levers fulcrumed between their ends and positioned longitudinally of the sled adjacent the runners thereof, guides fixed to the sled, downwardly projecting prongs at the rear ends of the levers movable in said guides, springs on the fulcrums of the levers engaging the levers and the sled, and normally maintaining the prongs in elevated position, handles at the forward ends of the levers adjacent the forward portions of the runners, pivoted handles adjacent the rear of the sled at the sides thereof, and devices movable with said handles and engaging the rear portions of the levers.

JOHN W. NOVAK.
